(57) **CLAIM**

The ornamental design for a tire, as shown and described.

DESCRIPTION

FIG. 1 is a perspective view of a tire showing my new design.

FIG. 2 is a front elevational view thereof, the rear elevational view being a mirror image of the front elevational view; and, FIG. 3 is a left side elevational view thereof, the right side elevational being a mirror image of the left side elevational view.

The broken lines in the figures represent features of the article of manufacture that form no part of the claimed design.
